CLAIM

The ornamental design for a raised garden bed as shown and described.

DESCRIPTION

FIG. 1 is a perspective view of a raised garden bed;
 FIG. 2 is an enlarged partial view of the delineated portion of FIG. 1;

FIG. 3 is a front elevation view of the raised garden bed;

FIG. 4 is a back elevation view thereof;

FIG. 5 is a side elevation view thereof;

FIG. 6 is an opposing side elevation view thereof;

FIG. 7 is a top plan view thereof;

FIG. 8 is a bottom plan view thereof;

FIG. 9 is an enlarged partial view of the delineated portion of FIG. 10; and,

FIG. 10 is another perspective view of the raised garden bed. The broken line showing of a raised garden bed is for the purpose of illustrating portions of the article and forms no part of the claimed design.

The broken line delineations in FIGS. 1, 2, 9, and 10 indicate the portions shown in enlarged views and form no part of the claimed design.
